(57) **CLAIM**

The ornamental design for holder for golf ball and accessory, as shown and described.

DESCRIPTION

FIG. 1 is a front perspective view of a holder for golf ball and accessory showing my new design;

FIG. 2 is a front elevational view thereof;

FIG. 3 is a left side elevational view thereof;

FIG. 4 is a top end elevational view thereof;

FIG. 5 is a right side elevational view thereof;

FIG. 6 is a rear elevational view thereof;

FIG. 7 is a bottom end elevational view thereof; and,

FIG. 8 is a front perspective view thereof in use holding golf ball and accessory.

The broken lines disclosed, on all the drawing figures, in the same line-weight as the structure lines, is showing standard stitching on the article. The light line-weight broken lines on FIG. 8 is for illustrative purposes only and forms no part of the claimed design.
